DESIGN FOR A LIGHTING-FIXTURE WALL BRACKET.

Application filed May 9, 1929. Serial No. 31,149. Term of patent 7 years.

To all whom it may concern:

Be it known that I, WALTER VON NESSEN, a citizen of the German Republic, and a resident of New York, county of Bronx and State of New York, have invented a new, original, and ornamental Design for a Lighting-Fixture Wall Bracket, of which the following is a specification, reference being had to the accompanying drawing, forming a part hereof.

In the drawing:

Figure 1 is a front view of the lighting-fixture wall bracket; and

Figure 2 is a side elevational view of the same.

The lining of the drawing is for the purpose of indicating shading, the design being more especially intended for porcelain wall brackets having smooth surfaces.

I claim:

The ornamental design for a lighting-fixture wall bracket substantially as shown and described.

WALTER VON NESSEN.
